UNITED STATES PATENT OFFICE.

HENRY ALLEN, OF SPRINGFIELD GARDENS, NEW YORK.

DESIGN FOR A WATCH-FOB, LOCKET, OR PENDANT.

55,735.

Specification for Design.

Patented July 13, 1920.

Application filed January 18, 1919. Serial No. 271,925. Term of patent 7 years.

To all whom it may concern:

Be it known that I, HENRY ALLEN, a subject of the King of England, and a resident of Springfield Gardens, Long Island, in the county of Queens and State of New York, have invented a new, original, and ornamental Design for Watch-Fobs, Lockets, or Pendants, of which the following is a specification, reference being had to the accompanying drawing forming a part thereof.

The figure is a plan view of a fob or pendant showing my new design.

I claim:

The ornamental design for a watch-fob, locket, or a pendant as shown.

HENRY ALLEN.
